UNITED STATES PATENT OFFICE.

WILLIAM I. BETTIS, OF LOS ANGELES, AND LEROY H. PERRY, OF GARDENA, CALIFORNIA; SAID PERRY ASSIGNOR TO SAID BETTIS.

WELL-CASING PROTECTOR.

Application filed January 5, 1925. Serial No. 707.

To all whom it may concern:

Be it known that we, WILLIAM I. BETTIS and LEROY H. PERRY, both of us being citizens of the United States, residing, respectively, at Los Angeles and Gardena, in the county of Los Angeles and State of California, have invented a new and useful Well-Casing Protector, of which a specification is set forth below.

10 In this specification, and the accompanying drawing, we will describe and show a preferred form of our invention and specifically mention certain of its more important objects. We do not limit ourselves to the 15 forms disclosed, since various changes and adaptations may be made therein without departing from the essence of the invention as hereinafter claimed; and objects and advantages, other than those specifically mentioned, are included within its scope.

Our invention relates to methods for protecting deep well casings from abrasion, and among its salient objects are; first, to provide practical means for preventing a drill 25 pipe and its joints from contacting with the wall of the casing, irrespective of length and straightness; second, to greatly reduce the tendency of drill pipe and casing to become crystallized as the result of vibration 30 and shocks due to contacts; third, to furnish a casing protector that is readily adapted for mounting upon a drill pipe; and, fourth, to supply a method for retaining the protector in proper position on the drill pipe 35 without mechanical fastening means other than its own inherent characteristics.

In the drilling of deep wells it is practically impossible to keep either the casing or the drill pipe in perfect alignment, or 40 the drill pipe concentric with the casing. As a consequence the drill pipe joints or couplings rub against the interior wall of the casing, and especially in the presence of gritty circulating fluid, very often wear 45 holes through the casing. This is particularly apt to happen when the drilling is hard, and it therefore is necessary to rotate the drill pipe for a relatively long time with very little longitudinal feed.

50 We have found that abrasion of the casing, under the foregoing conditions, may be practically eliminated by providing the drill pipe at intervals with rubber rings of sufficiently large external diameter, and in 55 sufficient number, to keep the drill pipe and

its joints from rubbing against the casing. It is well known that rubber is particularly adapted for water lubrication, and that water is always present in deep well drilling. Moreover, rubber rings thus used, by reason of their wet and slippery surfaces and their yielding nature, are unable to retain abrasive grit upon the surfaces and cannot damage the casing by rubbing 65 against it.

These principles are fully utilized and embodied by us in the present invention as illustrated in the accompanying drawing, in which—

Figure 1 represents in cross section a portion of a deep well with a drill pipe equipped with our invention therein;

Figure 2 is an enlarged elevation of the lower end of a drill pipe with a tool joint thereon, and indicates the manner in which 75 our casing protectors are applied thereto; the protector in this case is shown broken, and other parts in section, in order to better illustrate the construction; and

Figure 3 is a perspective view of a modified type of protector especially adapted for use where the internal diameter of the casing is relatively small compared to the outer diameter of the tool joints.

Similar reference numerals refer to similar parts throughout the several views.

Our invention comprises a plurality of resilient rubber rings 4 in combination with a drill pipe 5, upon which the rings are mounted at intervals. The rings are made 90 of a suitable composition adapted for withstanding wear and for being stretched under tension. The internal diameter 6 of the rings is normally less than the external diameter 7 of the drill pipe on which they 95 are to be mounted, so that they are adapted to tightly grip the pipe by the tension in the rubber. The external diameter 8 of the rings is greater than the external diameter 9 of the tool joints 10, or of the intermediate couplings 11.

The upper ends of the protecting rings are flared outwardly from the bore, as shown at 12, so as to enable them to be more readily forced over the tool joints and couplings. The outer ends of both of the latter are always rounded, as at 13, so that it is easily possible to force the rubber rings over them.

The protecting rings may be conveniently assembled upon the drill pipe by supporting 110

them upon a yoke, or upon an orifice plate 14, and lowering the drill pipe through them. When the tool joint or coupling has passed the ring the latter contracts upon the 5 drill pipe and is allowed to remain in the position shown in dotted lines 15, and also illustrated in section in Fig. 1. A sufficient number of rings are used in this way to insure that the drill pipe joints and couplings 10 will nowhere come in contact with casing 16 by reason of the lack of alignment of either the casing or drill pipe.

The modified form of our invention shown 15 in Fig. 3 is used where the external diameter of the ring is not much less than the internal diameter of the casing. In this type of ring the periphery is provided with longitudinal grooves 17, sufficiently large to permit passage of the circulating fluid therethrough 20 without substantial impediment. The grooves in this case simply increase the sectional area of the flow passages for the circulating fluid that otherwise passes through the annular spaces between the casing and 25 the peripheries of the rings.

It will be seen from the above description 30 that the use of our invention in no way changes or impedes the customary operations of drilling. On the other hand it not only greatly lengthens the life of tool joints 35 and couplings, but entirely obviates the danger of ruining the well by wearing holes through the casing, and thus destroying its function of sealing off the ground water. The cost of the protecting rings is relatively 40 small compared to the cost of the usual wear on tool joints and couplings; and compared to the cost of locating and repairing casing leaks, or of abandoning a well because of the impracticability of repairing the casing, the cost of the protecting rings is negligible.

We claim as our invention:

1. A well casing protector comprising a 45 ring of resilient material adapted for being sprung over a tool joint, and thereafter to grip a drill pipe; the bore of said ring

being outwardly flared at one end, and the outer diameter of the ring being greater than that of said joint. 50

2. A well casing protector comprising a ring of resilient material adapted for being sprung over a tool joint, and thereafter to grip a drill pipe; the radial thickness of said ring being such that, when gripping 55 said pipe, the outer diameter of the ring will be greater than that of said joint.

3. A well casing protector comprising a ring of resilient material adapted for being sprung over a tool joint, and thereafter to 60 grip a drill pipe; the outer diameter of said ring being greater than that of said joint, and the periphery of the ring being longitudinally grooved.

4. A well casing protector comprising a 65 longitudinally grooved ring of resilient material adapted for being sprung over a tool joint, and thereafter to grip a drill pipe; the bore of said ring being outwardly flared at one end; and the radial thickness of said 70 ring being such that, when gripping said pipe, the outer diameter of the ring will be greater than that of said joint.

5. In combination with a coupled drill 75 pipe, rings of resilient material gripping the pipe intermediate the couplings; the diameter of said rings when thus positioned being greater than that of said couplings; and said material being adapted for water lubrication and for resisting by its resiliency 80 the embedding of extraneous material therein.

6. In combination with a coupled drill 85 pipe, rings of resilient material gripping the pipe intermediate the couplings; the diameter of said rings when thus positioned being greater than that of said couplings; the peripheries of said rings being longitudinally grooved; and said material being 90 adapted for water lubrication and for resisting by its resiliency the embedding of extraneous material therein.

WILLIAM I. BETTIS.
LEROY H. PERRY.
